CLAIM

The ornamental design for a folding greeting card, as shown and described.

DESCRIPTION

FIG. 1 is a front view of a folding greeting card shown folded for mailing or other delivery in accordance with my design; FIG. 2 is a rear view of the folding greeting card shown folded;

FIG. 3 is a rear perspective view of the folding greeting card shown partially unfolded;

FIG. 4 is a side perspective view of the folding greeting card shown partially unfolded;

FIG. 5 is a reverse side view of the folding greeting card shown partially unfolded;

FIG. 6 is a perspective view of the folding greeting card shown partially unfolded;

FIG. 7 is a front view of the folding greeting card shown partially unfolded;

FIG. 8 is a plan view of the folding greeting card shown completely unfolded; and,

FIG. 9 is a plan view of the folding greeting card shown completely unfolded, illustrating the opposite side from FIG. 8.

The broken lines in the drawings depict fold lines and form part of the claimed design.
